UNITED STATES PATENT OFFICE

DAVID D. VANDERCOOK, OF CHICAGO, ILLINOIS, ASSIGNOR TO VANDERCOOK & SONS, OF CHICAGO, ILLINOIS, A PARTNERSHIP

REGISTER-PUNCH MECHANISM AND LIKE DEVICE

Application filed April 11, 1927. Serial No. 182,608.

My invention relates to register punch mechanism and like devices for use in connection with printing presses.

One of the objects of the invention is to provide a simple, practical and advantageous register punch mechanism of the class specified.

Another object of the invention is to provide a register punch mechanism which will secure accuracy by simple, readily operated and inexpensive devices.

In the accompanying drawings:

Fig. 1 is a vertical section of a register punch mechanism embodying my invention.

Fig. 2 is a plan view of the same.

Fig. 3 is a vertical section of an end portion of the device on an enlarged scale.

Fig. 4 is a section of the portion of the device shown in Fig. 3 but at right angles to the section of Fig. 3 and

Fig. 5 is a horizontal section of the mechanism shown in Fig. 4.

Referring to the drawings, I show a device having a suitable frame 1 provided with a bed or support 2 upon which a copper plate 3 or like device to be punched may be placed.

I also show microscope 5 supported at one end of the base 1, as by an upright or standard 6, mounted on said base 1. As a preferred arrangement a plate 7 is secured as by the screw 8 to the top of standard 6 and plate 7 has an aperture in which the lower end of the microscope 5 may be fitted. Upright 6 is preferably provided with a side

opening 9 adapted to admit light below the microscope to assist visibility. An end piece 10 is fitted into standard 6 so that its lower end is just above and adapted to be in contact with end of plate 3 to be punched.

The lower end of member 10 is provided with a punch opening 11 adapted to receive the punch after the same has passed through plate 3. Said member is also preferably provided with a side light opening 12 adapted to

admit light in proximity to the marking on the plate 3 so as to insure good sight of said marking.

A punch 15 is located below the end of plate 3 and is mounted to be raised and lowered so as to punch an aperture in said plate

3. As a preferred arrangement said punch 15 is carried by a vertically reciprocable holder 16, the punch being secured in said holder by a set screw 17, which latter is held in position by a plate 18 secured by screws 19. For raising and lowering holder 16 I show the same provided with rack teeth 20 adapted to cooperate with spur wheel teeth 21 on the annular ends 22 of an end lever 23, said member 22 being mounted on a pivot 24. Member 16 slides in a guideway formed by sides or cheeks 25 on standard 6.

Thus in operation the plate 3 may be adjusted in such position that the hair marks 26 will be visible through microscope 5 and by means of the microscope and the fact that it receives such an abundance of light, the adjustment of plate 3 may be absolutely accurate. At this time handle 23 is operated so as to elevate holder 16 and thereby cause punch 15 to pass upwardly through plate 3 and this punching operation shall take place at exactly the right point. Handle 23 shall then be operated so as to lower holder 16 and punch 15, after which plate 3 may be turned end for end and the other end punched in a similar manner.

It will be seen that the device is extremely accurate and inexpensive and readily operated.

It is understood that changes and modifications may be made without departing from the spirit of the invention.

What I claim is:

1. A register punch mechanism comprising a microscope and holder for holding the same above an article to be punched, in combination with a die and a punch arranged below the microscope and in vertical alignment therewith, a vertically reciprocable holder carrying the punch, and means for actuating said holder so as to force the punch upwardly through said article and die.

2. A mechanism of the class specified comprising a base providing a support for an article to be punched, a microscope mounted on a standard carried by said support, a die, a reciprocable holder carrying a punch and arranged below and in vertical alignment with the microscope, and a lever mechanism

for raising and lowering said holder so as to force the punch through said article and die.

3. In a mechanism of the class described, the combination with a punch and die, of a holder for a microscope having a side opening for the admission of light, said holder being arranged to hold the microscope over the die and in vertical alignment therewith, said side opening being adapted to admit light to the die.

4. In a mechanism of the class specified, the combination with a punch and die, of a holder for a microscope having two side openings for the admission of light, said openings facing at right angles to one another, said holder being arranged to hold the microscope over the die and in vertical alignment therewith, said side openings being adapted to admit light to the die.

20 5. In a mechanism of the class specified, the combination with a punch and die, of a holder for a microscope having two side openings for the admission of light, said openings facing at right angles to one another and being 25 one above the other, said holder being adapted to hold the microscope so that the article to be punched may be seen through the die and said side openings being adapted to admit light to the die.

30 6. In a mechanism of the class specified, the combination with a punch and die, of a holder for a microscope having two side openings for the admission of light, said openings facing at right angles to one another and being 35 one above the other, the lower opening being substantially at the surface of an article to be punched, said holder being adapted to hold the microscope so that the article to be punched may be seen through 40 the die and said side openings being adapted to admit light to the die.

7. A device of the class specified having a work holder, a sighting device above the work holder and marking mechanism comprising a punch below the work holder and a die above the work holder, said sighting device being in vertical alignment with the said punch and the said die.

50 8. A device of the class specified comprising a work holder, a sighting device, and marking mechanism comprising a member having an aperture adapted to serve as a light-admitting opening for the sighting device and also to serve as a die, and a punch arranged on the side of the work opposite the sighting device and said aperture and adapted to cooperate with the latter.

55 9. A device of the class specified having a work holder, a sighting device in the form of a microscope mounted above the work holder, and marking mechanism comprising a punch and die, one of which is arranged on one side of the work on the holder, and the 5 other arranged on the other side thereof, said

sighting device being in vertical alignment with the said marking mechanism.

In witness whereof, I hereunto subscribe my name this 6th day of April, A. D., 1927.

DAVID D. VANDERCOOK.
